WENDELL B. CAMPBELL, OF CINCINNATI, OHIO, ASSIGNOR TO THE PERKINS-CAMPBELL COMPANY, OF CINCINNATI, OHIO, A CORPORATION OF OHIO.

ART OF MAKING SHOES.

Application filed October 19, 1926. Serial No. 142,732. REISSUED

My invention relates broadly to the art of making shoes, and particularly to the art of making fancy shoes which have elements such as the vamps, quarters, facings, foxings, 5 heel covers and trimmings, which are composed in whole or in part of leather having different finishes or colors.

In the shoe manufacturing art there is a constant change in styles. This is particularly apparent in ladies' shoes, although of 10 recent years there has been a marked tendency of change in styles of shoes for girls, and men and boys also. The provision of shoes having style has become of such importance 15 in the industry that not only have the wearing qualities of the leather been regarded of less importance, but there has been a tremendous waste in scrap leather. The entire art 20 of making shoes has developed toward the almost complete sacrifice of quality and efficiency in the making of shoes in the trend toward the production of shoes having startling and unique color and finish combinations.

25 It may be regarded as a well known fact that every hide, which by nature is designed as a protective coating for an animal, has portions which are better suited for use in some parts of a shoe than in other parts. It 30 is my object to teach the art of utilizing leather hides and substantial portions thereof in such a manner as to selectively adapt those parts of the leather for use in those parts of shoes for which they are best suited, irrespective of the finish applied thereto, which has 35 not been possible without the scrapping of untold quantities of valuable leather in the past.

It is my object in this new art to disclose how the individual component parts of a 40 shoe may be taken from that part of the skin for which the leather is best adapted. It is further my object to greatly facilitate the dyeing and coloring of those parts of the shoes which require coloring.

45 It is my object also to greatly facilitate the embossing of patterns on the portions of shoes which require embossed patterns. It is an object to decrease very materially the expense of special treatments such as scotch 50 graining in those parts of shoes which require this type of leather. In addition to showing how comparatively great savings may be

made, it is further my object to teach an art which will greatly widen the range of decorative effects which may be obtained. 55

It is also the object of my art to greatly facilitate the producing of various finishing effects by cheaper equipment and much less ponderous and dangerous machinery than is now required. 60

In order to explain the advantage of cutting out the individual component parts for shoes from a side of leather so as to utilize the portion of the hide best suited for a particular purpose in a shoe, I have illustrated one 65 sample shoe, and have shown how the component parts for shoes of such a pattern may be efficiently cut from an unfinished hide or substantial part thereof.

Referring to the drawings:— 70

Figure 1 is a plan view of a side of leather showing in shaded areas the portions of the side which can be utilized for the various shoe elements.

Figure 2 is a plan view showing how the 75 side of leather shown in Figure 1 could be cut into shoe elements, such as would be required for assembling the shoe shown in Figure 3.

Figure 3 is a lady's shoe of a pattern which 80 has been selected for purposes of illustration.

The side of leather illustrated in Figures 1 and 2 is a calf skin in which the area A shaded with diagonal lines is the thick unwrinkled portion called the butt of the side. 85 This portion is available for shoe vamps. The nearer to the lower end of the side in which the vamps are cut will ordinarily determine the quality of the shoe in which the vamps are to be used. The portion B of the 90 side shaded with vertical lines is the portion which can be used for shoe quarters and what is called the foxing. The remaining portion of the side is available for facing or saddle pieces and for tongues. The number of pairs 95 of shoes which can be cut from the side depends primarily on the number of vamps which can be cut from it, as all the portions available for quarters and foxing, saddles and tongues could be cut from the portions 100 available for vamps.

Referring to the sample shoe which we have illustrated in Figure 3: The shoe is a lady's shoe having a vamp V of scotch

grained leather with a flower medallion M embossed in the center of the tip. The quarter Q of the shoe is of black suede formed by processing the flesh side of the leather. 5 The saddle or facing S as it is called in the trade is of plain green colored leather. The foxing F is of green colored leather having a reptilian design, as indicated, embossed on it. The tongues T are of plain black grained 10 leather.

Figure 2 illustrates how a shoe cutter would proceed to cut up such a side of leather for manufacturing shoes according to the sample indicated. The pieces which are to 15 make up component elements of the shoes are marked in sequence, V—L—1 indicating the vamp portion for the left shoe of the first pair of shoes, V—R—2 indicating the vamp portion for the right shoe of the first pair. 20 It will be noted that the side indicated provides ten vamps marked in sequence up to V—L—10 and V—R—10 so that five pairs of shoes may be made.

The hide has some cuts and markings such 25 as salt stains and wire fence scratches, which are indicated at C which it will be noted the cutter cuts almost entirely into suede pieces and scrap of such size as to be utilizable.

The foxing parts are indicated at F, the 30 foxing for the first pair of shoes consisting of the parts F—L—1, F—L—2, F—R—1 and F—R—2. Each pair of shoes has a right shoe with a right and left foxing, and a left shoe with a right and left foxing, the right 35 foxing for the right shoe being cut on the same pattern as the left.

The only scrap remaining from the side 40 illustrated will be the neck portion which is of such comparative large size as to be available for many purposes, both in the shoe manufacturing industry and in other industries, and under my process can be used for linings for the same shoes, and properly finished therefor after cutting.

45 Basically all leather made from one particular class and of one particular tannage is the same, regardless of the finish finally applied. All hides must first go through a process to remove the hair, and then through 50 some tanning process. My new art contemplates the usual de-hairing process and a tanning operation. If I use vegetable tanned hides, the hides should be brought to the 55 fully tanned condition, known as the crust condition in the trade. The hides must be then set, shaved, stretched and dried. If chrome tanned hides are used, the hides should be given the usual pickling and chrome bath after de-hairing. At this stage in the 60 present practice, the hides are fat liquored, stretched and dried, and must then be given the finishing treatment required at once, or else it will be impossible to preserve the proper receptive condition of the hides.

65 According to my process, a suitable treat-

ment is given to the hides to permit of their being held, and subsequently given a finishing treatment. One way of doing this with chrome leathers is to employ a mixture of 2% of lactic acid with the chrome liquor. The 70 hides may also be conditioned after the chrome bath by soaking in an aqueous bath containing 15% salts, 5% Glauber's salt, 2% glucose and 2% of glycerine. Alum tanned hides are given a similar treatment, with the 75 substitution of an alum bath and treatment instead of a chrome bath.

When the hides have been so treated as to 80 permit of reconditioning, which is usually done by wetting the hides, they may be given the fat liquor treatment, stretched and dried, or they may be left in their tanned condition, without fat liquoring, and this increasing of fatty content given to the hides before or after they are cut up into shoe parts, or two 85 fat liquor treatments can be given, one before shipment, and the other later.

If other tanning treatments are used the 90 leather should be prepared in such condition that it may be subsequently finished, and as 95 my art contemplates the finishing of individual component parts of shoes after they have been cut to shape and size for shoes into which they are to be used any tanning treatment which leaves the leather in such a condition that it cannot be subsequently finished, 100 would require an immediate cutting into shoe parts following the normal fat liquoring, or else finishing with colors embossing, graining, and the like, could not be effectively applied in accordance with my process.

It is contemplated that as ordinary practice, the shoe manufacturer will receive his 105 hides in such a condition that he can re-wet them or recondition them, so that they will properly receive the desired finish.

The reason why care should be taken and departure from present methods of finishing 110 hides followed, is that according to my invention I apply the finish to the pieces after they are cut from the hide, thus obtaining the correct finish for the correct type of leather with a minimum of waste, and the other numerous advantages to be pointed out.

I desire to cover in my process any mode of 115 preparing leather which will permit of its being held sufficiently before finishing to permit of shipment, storage and cutting up into various types of shoe parts, and have recited but one method as applied to chrome and alum 120 leathers, which is typical of the treatment which should be applied to other types of tanned leathers.

Of course in an instance in which the shoe 125 manufacturer operates a tannery and could conceivably regulate his production in such a way that hides ready to be finished could be delivered to the cutting room of the shoe factory without delay, and could be cut up promptly, it would not be necessary in order 130

to enjoy the advantages of my invention to 5 prepare the hides for delivery in a condition which would permit reconditioning them for a finishing treatment. The impracticability of such a practice would indicate the normal necessity for preparing the hides for reconditioning at the tannery.

Also some methods of tanning may not result in leaving the hide in such a condition 10 that it cannot be given a finishing treatment because of its having so "set" in its condition that further treatment is impossible, which would be the result of the regular practice of today.

15 In any event, the hide in a condition which will permit of its being given whatever finish is desired, is cut up into shoe parts while in this condition. In my drawing and explanation thereof, I have fully indicated in a 20 typical piece of leather, the factors which will control in the cutting. After the cutting, the individual pieces of leather are given the desired finishing, in which finishing a wide variety of treatments may be given, as brushing 25 with color, dipping into color, japanning and baking, embossing, sanding, graining, etc.

The art of making shoes which I have disclosed is primarily advantageous because it 30 eliminates the finishing of much leather which will not be available for shoes even after it is finished. Then it brings the units down to such a size and shape that they can be given the treatments such as sanding, coloring 35 and embossing much more economically than was heretofore possible. It also avoids the difficulty in matching colors or embossed patterns in cutting shoe elements from finished sides. Finally it enables the cutting of shoes 40 with a much wider range of possibilities of using the particular part of the hide in that part of the shoe for which it is best adapted.

The embossing of the leather pieces, such as is required to emboss and grain the vamps, 45 and to emboss the reptile marking, only requires a small embossing and plating roller or plate sufficiently large to handle a single element, instead of a cumbersome, expensive and dangerous mechanism. The disposition 50 of the markings in a certain portion of the shoe may further be accurately controlled. If, as has been standard practice in the past, an entire hide were to be embossed with a flowered design as is shown on the shoe tip in 55 Figure 3, it would be almost impossible to so cut the vamps that the right quality of leather would be available and at the same time the flowered design would occur in the center of the tip. In entire sides of leather 60 which are embossed with reptilian designs, the cutting and matching of the pieces for each shoe is a task that is most arduous, and as a result, efficiency in cutting is impossible.

In applying a color coating to small pieces 65 of leather, such as are required for the ele-

ments of single shoes, colors which because of their quick drying qualities, cannot be used on entire sides, may be employed. I prefer to use strong pigment coatings, which may be applied with one stroke across the piece, with 70 the swab or brush. This enables me to make a very uniform shade of color which avoids all difficulty of matching colors in parts for the same pair of shoes. Also it is impossible to obtain a uniform color on an entire hide or 75 substantial portion thereof, without repeated thin coatings very carefully applied.

There are a number of pigments and other processes which can only be used in one coating which I am also able to use, so that a very 80 wide range of shades and intensities may be achieved.

Certain parts of patent leather shoes require very particular selection of the leather composing it, and my art contemplates the 85 selection of the parts prior to the application of the patent leather finish. After cutting out the elements, I japan them and then bake them in a japanning oven, where being in such small units, accurate control of the heat 90 is much more readily accomplished and better work can be done.

In considering the advantages of selecting the leather for shoe elements prior to the finishing operation, it should be noted that I 95 have taught an art which is economically of great importance. Although the market price of leather is constantly fluctuating, if we assume a certain price per pound at the tannery of unfinished leather, when a finishing treatment such as dyeing and coloring, embossing with a reptile pattern, or scotch 100 graining has been accomplished, the cost of the leather has increased many times.

For example, in the particular shoe which I have illustrated, the cost of the untreated leather would be only about one third of the cost if the various finishing treatments had 105 been applied. This is because for coloring an entire or substantial portion of a hide from six to twelve coatings of thin pigment have to be applied as has been stated, and a strong pigment such as I employ for coloring with a single coat cannot be applied to an entire side of leather. If a side of leather is to be 110 embossed with a reptile design, there is required a very expensive embossing die. If the hide is to be scotch grained, the expense 115 (which I minimize because I treat only those parts which are to be scotch grained in the finished shoe) is wasted if the entire hide is scotch grained, because the only part of the leather which could be utilized would be the 120 vamp portion, in my typical shoe.

Actual calculations which I have had verified again and again by different shoe manufacturers show that in the making of fancy shoes, often there is a cutting scrap of as high as sixty per cent. Leathers which are bought 125 because certain types of shoes require certain 130

types of elements therein accumulate until inventories of leather are carried which represent huge investments which are reflected in the high price of shoes. My art, which 5 teaches the selective cutting of entire or substantial portions of hides into those parts of the shoes for which the particular parts cut are best adapted, not only provides a very material saving in more efficient cutting, but 10 it avoids the expensive treatment of much leather which cannot be used after treatment. The economies of finishing the individual shoe elements in accordance with the requirements of the shoe make the possibilities of applying a wide variety of finishes much more economically than was heretofore possible. In dyeing and subsequently coloring an entire hide or a substantial part thereof even though six to twelve coats of weak pigment 15 have been applied, when shoe elements are cut from the side subsequently, it is almost impossible to match the colors without great loss in scrap. In applying one coating of a strong color, all matching difficulty is avoided, and there is a much wider range of coloring possibility than where weak colors are used.

In embossing entire hides or substantial parts thereof, the problem of arranging the 30 embossed elements so that they will appear in certain positions on the shoes is also a source of great waste, and also results in the use of leather not suitable for a particular element because of its quality, which has a 35 deleterious effect on the shoe.

In selectively cutting the elements for a shoe prior to the finishing of the leather, I am able to split the hide and prepare the outer side with one finish and the inner side 40 with another finish, which again makes a material saving in the leather required.

In the claims which follow, I have used the term "hide" to imply either what are known in the trade as hides or skins. I have 45 used the term "finish" in the sense of the treatment which in the past has been given to tanned hides prior to cutting into shoe parts. Under finishing, I include dyeing, color coating, applying a patent leather finish, graining, embossing and any other treatments which have been applied to leather sides and substantial portions thereof prior to the cutting into shoe elements. As I have used the word finish, I differentiate from 50 the assembly of the elements into shoes which in some localities is called the finishing of the shoes.

Having thus described my invention what I claim as new and desire to secure by Letters Patent is:—

1. Those steps in the process of manufacturing shoes which consist in tanning and preparing a hide to receive a surface finish, then cutting out from the hide dissimilar

parts for shoe uppers, using those parts of 65 the hide for the particular shoe parts for which the quality of the particular part of the hide cut out is best adapted, then independently finishing each part with its desired finish after the parts are cut before 70 finally making the parts into the uppers of shoes.

2. Those steps in the process of manufacturing shoes which consist in tanning and preparing a hide to properly receive a leather 75 dye, then cutting out from the hide parts for shoe uppers, using those parts of the hide for the particular shoe parts for which the parts of the hide cut out are best adapted, then independently dyeing each part a desired color after the parts are cut and surface finishing the dyed parts prior to their assembly into shoes.

3. Those steps in the process of manufacturing shoes which consist in tanning and 85 preparing a hide to properly receive a surface finish, including such steps as will permit the hide to be reconditioned by wetting, subsequently wetting and reconditioning the hide, then cutting out from the hide 90 parts for shoe uppers using those parts of the hide for the particular shoe parts for which the parts cut out from the hide are best adapted, then independently surface finishing each part with its desired finish 95 after the parts are cut before finally making the parts into shoe uppers.

4. Those steps in the process of making shoes which consist in tanning and preparing a hide to properly receive a surface finish, 100 then cutting out from the hide parts for shoe uppers, using those parts of the hide for the particular shoe parts for which the quality of the particular part of the hide cut out is best adapted, then independently fat 105 liquorizing and finishing each part with its desired finish prior to the assembly of the parts in a shoe.

5. Those steps in the process of making shoes which consist in tanning and preparing a hide to receive a color coating, then 110 cutting from the hide parts for shoe uppers using those parts of the hide for the particular shoe parts for which the parts of the hide cut out are best adapted, and then independently surface coating each part with a single application of color prior to the assembly of the parts in a shoe.

6. Those steps in the process of making shoes which consist in tanning and preparing 120 a hide to receive a surface finish, then cutting out from the hide parts for shoe uppers using those parts of the hide for the particular shoe parts for which the parts cut out are best adapted, and then coloring and independently scotch graining those parts which are to have a scotch grain in the finished shoe 125 prior to the assembly of the shoe.

7. Those steps in the process of making shoes which consist in tanning and preparing a hide to receive a surface finish, then splitting the hide, then cutting out from one 5 split portion parts for shoe uppers using those parts of the hide for the particular shoe parts for which the parts of the hide cut out are best adapted, then cutting out from the other split portion other parts for shoes, then independently finishing each part 10 with its desired finish prior to the assembly of the parts in a shoe.

WENDELL B. CAMPBELL.
